WILHELM SCHMIDT, OF CASSEL-WILHELMSHÖHE, GERMANY, ASSIGNOR TO
SCHMIDT'SCHE HEISSDAMPF-GESELLSCHAFT M. B. H., OF CASSEL, GERMANY, A CORPORATION OF GERMANY.

ENGINE-GOVERNOR.

1,090,417.

Specification of Letters Patent. Patented Mar. 17, 1914.

Application filed December 16, 1911. Serial No. 666,275.

To all whom it may concern:

Be it known that I, WILHELM SCHMIDT, a subject of the King of Prussia and Emperor of Germany, and resident of Cassel-
5 Wilhelmshöhe, Germany, have invented certain new and useful Improvements in Engine-Governors, of which the following is a specification.

My invention relates to engine governors for reciprocating engines and is especially adapted and intended for engines of the type shown in my German Patent No. 76,651 of September 4, 1894. In the engine there disclosed the steam or driving medium is admitted by 10 the aid of an inlet element which normally tends to remain open but which closes automatically under the influence of pressure changes produced by the moving piston with which the inlet element is associated. In 15 such engines the quantity of steam admitted to the cylinder is increased or decreased in accordance with the lift of the inlet element or in other words, the original cross section of the inlet opening is made greater or less 20 with the lift of the inlet element so that the time at which the excess pressure necessary to close the inlet element becomes sufficiently great is correspondingly earlier or later. Governing in this way one is limited by the 25 amount of the normal lift of the inlet organ, *i. e.*, by the normal area of the inlet opening since regulation with very small normal lifts is unreliable.

The object of my invention is to provide a 30 governor of the general type specified in which the lift of the inlet element shall be the same for all values of the steam charge. In this way the governing action is equally reliable for very small lifts (say $\frac{1}{2}$ mm. and 35 less) when a valve is used as the inlet organ as for very large lifts when a sliding piston is used for the inlet element. When such sliding piston is used as an inlet element there is obtained the additional advantage 40 that the lift may be greater than the height of the inlet opening.

The exact character of my invention will be better understood by reference to the drawing accompanying which is hereby 45 made a part of this specification, and in which—

Figure 1 represents a longitudinal cross section through one end of the cylinder and

piston embodying a preferred form of the invention and Fig. 2 represents a corresponding cross section showing a modification thereof.

Referring to Fig. 1 the steam cylinder *a* is provided with a piston *b* a steam inlet *a*, *a*, and outlets *a'* controlled by said piston. In the cylinder end is a ring-shaped inlet opening *a''* controlled by a ring valve *c* lying in the steam inlet chamber *d*. This inlet chamber is provided with a valve piston *f*, attached to and forming part of the ring valve *c*, the inside of which is hollow and permanently connected with the inlet chamber *d*. The piston *f* functions in a cylindrical chamber *e* which I call the regulating chamber. The inlet chamber *d* and the regulating chamber are connected together by means of a canal or by-pass *g*, whose section may be adjusted by means of a screw *g'*. A tube *h* at the end of regulating chamber *e* on the outer side of the valve piston is provided which connects said regulating chamber with the atmosphere or with a suitable steam collector. In this tube is inserted a pressure regulator which consists of a threaded spindle *i* provided with a valve cone *i'* and a housing *i''* provided with a passage *i'''*. The threaded spindle *i* has attached thereto an arm *i''''* controlled by a regulator or in default thereof by hand. A fine stream of fresh steam whose pressure is regulated by the pressure regulator *i*, *i''''* constantly flows through the passage *g*, the regulating chamber *e* and the tube *h*. The pressure of fresh steam within the hollow piston *f* tends constantly to raise the valve *c* from its seat. This pressure is opposed to the pressure operative upon the top of the piston in the regulating chamber *e*. The dimensions of the two piston surfaces are so chosen that the difference between the pressure in the inlet chamber *d* and that in the regulating chamber *e* may be made very small.

As the piston *b* of the engine moves from the steam inlet toward the steam outlet a throttling in the opening *a''* of the valve takes place which throttling increases with increasing speed of the piston. In consequence there is in the cylinder a smaller pressure than in the inlet chamber. As soon as the difference between the pressure in

front of and behind the valve *c* is sufficiently great to overpower the pressure effective to raise the valve such valve *c* will close and remain closed during the expansion and the exhaust. It also remains closed during a portion of the reverse stroke of the piston and only opens when the compression pressure has reached a certain value.

If the arm *i*¹ of the pressure regulator is rotated so as to reduce the cross section of the passage *i*² then the pressure in the regulating chamber *e* will increase. Consequently the force operating to open the valve *c* will become less. The valve will therefore close more quickly than before and the steam charge will be smaller. Conversely if the arm *i*³ of the pressure regulator is rotated in the opposite direction the pressure in the regulating chamber will decrease. The force tending to open the valve will become greater and the valve will close later so that the steam charge will be increased.

Instead of employing a special passage *g* the regulating chamber *e* and the inlet chamber *d* may be united by providing a suitable amount of play between the piston *b* and the cylindrical wall of the regulating chamber *e*.

In the modification shown in Fig. 2 the steam inlet is controlled by a piston *m*. This slides in a cylindrical passage or chamber which opens at the cylinder end into the cylinder. Steam from the inlet chamber *d* passes or may pass through inlet openings or passages *p* into the chamber *o* and thence into the steam cylinder. The upper part of chamber *o* constitutes a chamber *o'* which is permanently united by passage *o*² with the inlet chamber *d*. The regulating piston *m* is connected to the valve piston *f* which latter functions in the cylindrical chamber *e* and is connected by a stem *n* with an air-cataract *r r'*. The passage *g*, as in the previous modification, joins the regulating chamber *e* with the inlet chamber and the tube *h* serves for the passage of steam from the regulating chamber. In the tube *h* a pressure regulator should be inserted as in Fig. 1. In order to save space the same has been omitted from Fig. 2. When the piston takes the position shown in the drawing, the fresh steam pressure upon its under side tends to hold it in its higher position. Upon this piston the fresh steam in chamber *o'* and the fresh steam of lower smaller pressure in regulating chamber *e* work oppositely to the pressure of the steam upon the under side thereof. The dimension should be so chosen that the effective pressure on the under side of the piston will control. As the engine piston *b* moves from the steam inlet toward the steam outlet, there will take place a throttling of the inlet steam which throttling will increase with

the increasing velocity of the piston. As soon as the pressure in the steam cylinder becomes sufficiently small to permit the pressure acting in the chambers *o'* and *e* upon the pistons *m f* to overcome the effective pressure on the under sides of the piston, said piston will be moved into the position indicated by the dotted lines in which position the inlet passage *p* is closed. During the compression pressure the piston will again be raised. The air-cataract *r r'* serves to limit the extent of movement of the pistons *m f*.

It is obvious that my invention is not restricted to the particular modification shown in the drawing. In particular the form of the regulating piston *f* is not essential and it might, for example be a piston of the membrane type. Furthermore the force tending to keep the inlet element open need not be taken altogether from the driving force of the machine, but a spring may be used if desired in combination with said driving force. It is also not necessary to employ the driving force of the machine as a pressure means in the regulating chamber *e*, but any other convenient medium under pressure may be employed for this purpose.

Having described my invention, I claim:

1. The combination, with an engine cylinder provided with a piston, an inlet chamber at the end of said cylinder, an inlet opening from said inlet chamber into said cylinder, and an outlet, of controlling means for said inlet opening said means comprising a valve, means for leading steam from the inlet chamber to both sides of said valve, and a steam outlet from the outer side of the valve piston.

2. The combination, with an engine cylinder provided with a piston, an inlet chamber at the end of said cylinder, an inlet opening from said inlet chamber into said cylinder, and an outlet, of controlling means for said inlet opening, said means comprising a valve, means for leading steam from the inlet chamber to both sides of said valve, a steam outlet from the outer side of the valve, and means for regulating the steam pressure on said outer side of said valve.

3. The combination, with an engine cylinder provided with a piston, an inlet chamber at the end of said cylinder, an inlet opening from said inlet chamber into said cylinder, and an outlet, of controlling means for said inlet opening said means comprising a valve, means for leading steam from the inlet chamber to the inner side of the valve, a regulating chamber in which said valve moves, a contracted steam passage between said regulating chamber and the inlet chamber, and a steam outlet from the regulating chamber.

4. The combination, with an engine cylinder provided with a piston, an inlet chamber at the end of said cylinder, an inlet open-

ing from said inlet chamber into said cylinder, and an outlet, of controlling means for said inlet opening, said means comprising a valve piston, means for leading steam 5 from the inlet chamber to the inner side of the valve piston, a regulating chamber in which said valve piston moves, the walls of said chamber being spaced from the piston so as to constitute a passage between said 10 regulating chamber and said lower side of the valve piston, and a steam outlet from the regulating chamber.

5. The combination, with an engine cylinder provided with a piston, an inlet chamber 15 at the end of and opening into said cylinder, and an outlet, of a regulating chamber separated from the interior of the cylinder and adapted to contain a pressure fluid, means for varying the pressure of said 20 fluid according to the loading of the engine, and a valve controlling the opening between inlet chamber and cylinder, said valve having one surface open to the interior of the cylinder and another surface open to the 25 regulating chamber, said surfaces being so proportioned that the valve will periodically

open and close as the piston moves to and fro.

6. The combination of an engine cylinder provided with a piston, an inlet chamber at 30 the end of and opening into said cylinder, and an outlet, of a regulating chamber adapted to contain a pressure fluid and having an inlet and outlet channel, a throttling arrangement in one of said channels for 35 varying the pressure of said fluid according to the loading of the engine, and a valve controlling the opening between inlet chamber and cylinder, said valve having one surface open to the interior of the cylinder and 40 another surface open to the regulating chamber, said surfaces being so proportioned that the valve will periodically open and close as the piston moves to and fro.

In testimony whereof, I have hereunto 45 set my hand in the presence of two subscribing witnesses.
